TANK FILLING MEANS

James E. Browning, San Antonio, Tex., assignor
to Browning Laboratories, Inc., San Antonio,
Tex., a corporation of Texas

Application December 2, 1944, Serial No. 566,298

4 Claims. (Cl. 137—104)

1

The invention aims to provide an exceptionally simple and inexpensive, yet a highly dependable mechanism for connection with a liquid tank to permit filling to a predetermined level only, leaving sufficient head space in the tank for liquid expansion without possibility of producing a dangerously high pressure, the invention being, therefore, well adapted for tanks containing butane or other liquefied gas, for domestic or industrial use.

In carrying out the above end, a further object is to embody the invention in one simple unit easily attachable to a tank and easily removable therefrom, for repair.

Figure 1 is a side elevation of the invention attached to a tank, showing the parts in substantially empty-tank position.

Fig. 2 is an enlarged vertical sectional view with the parts positioned as in Fig. 1.

Fig. 3 is a fragmentary sectional view showing the relation of parts as the tank is being filled.

Fig. 4 is a view similar to Fig. 2 but illustrating the manner in which supply of liquid to the tank is prevented when the tank has been filled to a predetermined level.

Fig. 5 is a detail sectional view illustrating the manner in which the liquid valve is reset to open position during lowering of the liquid level in the tank.

Fig. 6 is a detail vertical section on line 6—6 of Fig. 3.

Fig. 7 is a detail horizontal section on line 7—7 of Fig. 2.

A preferred construction has been illustrated and will be rather specifically described, with the understanding, however, that within the scope of the invention as claimed, variations may be made.

A valve casing 3 is provided, said casing having a threaded portion 9 for reception in the neck 10 of a tank 11, the upper end of said casing being internally threaded for connection with a liquid-conducting pipe 12. The lower end of the casing 3 is reduced at 13 and provided with a downwardly projecting stem guide 14 of tubular form, the lower end of this guide being suitably slotted vertically as at 15 to provide it with downwardly extending rigid arms between which to mount parts hereinafter described. Above the stem guide 14, liquid discharge openings 16 are formed in the casing, and above these openings said casing is formed with an internal upwardly facing valve seat 17. Cooperable with this seat is a gravity-lowered valve 18 having a stem 19 which is slidably received in the stem guide 14.

A float arm 20 is pivoted at 21 to the lower end

2

of the stem guide 14, said arm being provided, in the present disclosure, with an upstanding plate 22 through which the pivot 21 extends, said plate being received in the slot 15. The outer edge 23 of this plate is curved and constitutes a cam for pushing upwardly on the valve stem 19 as the float arm 20 lowers, as shown in Fig. 5, thus moving the valve 18 toward open position. The lower end of the stem 19 preferably carries an anti-friction ball or the like 24 to contact with the cam 23.

Two L-shaped latches 25 are pivotally mounted upon the pivot 21 at opposite sides of the plate 22, the vertical arms 26 of said latches being positioned to swing under the valve stem 19 when the valve 18 has been fully opened by descent of the float arm 20, as shown in Fig. 2. The upper extremities of the arms 26 are formed with stop fingers 27 which limit the movement of the latches to operative position, and the lower end of the stem 19 is preferably vertically grooved at 28 to receive said fingers when the valve 18 stands open. These grooves also receive the inner edges of the arms 26 when the latches are released and the stem 19 lowered as seen in Fig. 4.

The horizontal arms 29 of the latches 25 project beyond the stem guide 14 and are rigidly connected by a transverse pin 30. The lower end of a safety latch 31 overlies the pin 30 when the latches 25 are in operative position and holds said latches 25 against possible accidental release due to any friction between them and the plate 22 as the float arm 20 rises and jostles laterally due to turbulence of the ingoing liquid. The latch 31 is pivoted to the stem guide 14 at its upper end, as shown at 32. This upper end of the latch 31 is formed with an upstanding stop finger 33 which limits the movement of said latch to released position, and the lower end of said latch is provided with a finger 34 which strikes the pin 30 and limits the movement of said latch to operative position.

The plate 22 of the float arm 20 has an extension 35 to thrust against the pin 30 when said float arm 20 has swung upwardly to a predetermined extent, and said extension has a cam edge 36 which strikes the finger 34 of the safety latch 31 immediately before said extension contacts with said pin 30. It thus follows that when the float arm 20 has been raised to the predetermined level, the cam 36 releases the safety latch 31 from engagement with the pin 30 and the extension 35 then thrusts upwardly on said pin 30, thus rocking the latches 25 from the operative position shown in Figs. 2 and 3, to a position at which they release the stem 19 and allow the valve 18 to close, as shown in Fig. 4.

The float arm 20 is formed with two thrust shoulders 37 to abut the outer edges of the arms 26 of the latches 25 when said float arm 20 is fully lowered, said shoulders then serving to force said arms 26 under the valve stem 19, which stem has been raised to valve open position by the cam 23 during descent of said float arm 20, as will be clear from Fig. 2. The shouldered end of the float arm preferably carries a suitable counterbalance 38.

To explain the operation of the invention, we will assume that the tank 11 is about empty, the float arm 20 then occupying a completely lowered position (see Figs. 1 and 2). The latches 25 then hold the valve 18 in open position as seen in Fig. 2, and said latches are held by the safety latch 31. Liquid may now be admitted as indicated by the arrows in Fig. 2 and as the liquid level in the tank rises, the float arm 20 swings idly upward as illustrated in Fig. 3. When the liquid level has risen to the predetermined extent, however, the cam 36 first releases the safety latch 31 and the float arm extension 35 then pushes upwardly upon the pin 30, thus swinging the two latches 25 to released position and allowing the valve 18 to close as seen in Fig. 4. This closing occurs when there is still a safe head space in the tank 11, to permit liquid expansion without danger. As liquid is withdrawn from the tank 11, the float arm 20 descends, and during this descent, the cam 23 acts upwardly on the stem 19, moving the valve 18 again toward open position. When the valve has been completely opened, the shoulders 37 swing the latches 25 again to operative position, the parts being then in the relative positions shown in Fig. 2, to permit the tank to be again filled.

The reference character 39 merely represents a projecting pin near the lower end of the stem 19 to prevent this stem from rotating, insuring that its grooves 28 shall remain in cooperative relation with the latches 25.

From the foregoing, taken in connection with the accompanying drawings, it will be seen that novel and advantageous provision has been made for carrying out the objects of the invention, and attention is again invited to the possibility of making variations within the scope of the invention as claimed.

I claim:

1. A tank-filling means comprising an elongated casing to extend through an opening in a tank, said casing having a liquid inlet at its outer end, a longitudinal stem guide at its inner end, a liquid outlet between said inlet and said stem guide, and an outwardly facing valve seat between said inlet and outlet, the inner end of said stem guide being provided with a rigid arm projecting longitudinally inward and laterally offset from the axis of said guide, an inwardly closing valve cooperable with said seat and having an attached stem extending longitudinally through said stem guide, a cam directly cooperable with the inner extremity of said stem for forcing the latter to valve-open position, a transverse pivot mounting said cam on said rigid arm, a float arm secured to said cam for operating it, a right angular latch pivotally mounted at its angle on the aforesaid pivot at one side of said cam, said latch having a longitudinal arm extending toward said casing for end-to-end abutting relation with said stem to hold the latter in valve-open position, said latch also having a second arm projecting laterally, thrust means on said float arm at one side of said pivot to abut said

longitudinal arm of said latch and move the latter to operative position when said float arm descends to valve-open position, and other thrust means on said float arm at the other side of said pivot to abut said lateral arm of said latch and move the latter to released position when said float arm ascends to a predetermined position.

2. A tank-filling means comprising an elongated casing to extend through an opening in a tank, said casing having a liquid inlet at its outer end, a longitudinal stem guide at its inner end, a liquid outlet between said inlet and said stem guide, and an outwardly facing valve seat between said inlet and outlet, the inner end of said stem guide being provided with a rigid arm projecting longitudinally inward and laterally offset from the axis of said guide, an inwardly closing valve cooperable with said seat and having an attached stem extending longitudinally through said stem guide, a flat plate at the inner extremity of said stem and having a cam edge directly cooperable with said extremity for forcing said stem to valve-open position, a transverse pivot mounting said plate on said rigid arm for pivotal movement in a plane extending longitudinally of said casing, a float arm secured to said plate for operating it, and a right angular latch pivotally mounted at its angle on the aforesaid pivot at one side of said plate, said latch having a longitudinal arm extending toward said casing to abut the inner extremity of said stem to hold the latter in valve-open position, said latch also having a second arm projecting laterally, the aforesaid plate having a thrust shoulder at one side of said pivot to abut said longitudinal arm of said latch and move the latter to operative position when said float arm descends to valve-open position, said plate having another thrust portion at the other side of said pivot to abut said lateral arm of said latch and move the latter to released position when said float arm ascends to a predetermined position.

3. A structure as specified in claim 1; together with a safety latch pivotally mounted on said stem guide for engagement with said lateral arm of the first mentioned latch to positively hold the latter against accidental release during ascent of said float arm, said float arm having a portion to contact with and release said safety latch as said float arm approaches said predetermined position.

4. A structure as specified in claim 2; together with a safety latch pivotally mounted on said stem guide for engagement with said lateral arm of the first mentioned latch to positively hold the latter against accidental release during ascent of said float arm, said plate having a cam portion to contact with and release said safety latch as said float arm approaches said predetermined position.

60 JAMES E. BROWNING.
